UNITED STATES PATENT OFFICE.

THEODORE HAVILAND, OF AMBAZAC, FRANCE.

DESIGN FOR A DISH.

SPECIFICATION forming part of Design No. 22,200, dated February 7, 1893.

Application filed January 10, 1893. Serial No. 457,952. Term of patent 7 years.

To all whom it may concern:

Be it known that I, THEODORE HAVILAND, a citizen of the United States, residing at Am-bazac, in the Department of Haute Vienne and Republic of France, have invented and produced a new and original Design for Dishes; and I do hereby declare the following to be a full, clear, and exact description of the same, reference being had to the accompanying drawing, forming a part thereof, wherein the figure illustrating my design shows a side elevation of a covered dish.

The leading or characteristic features of my design consist in the handle which rises from the lower part of the dish in a gradual upward direction to a point above the margin thereof and then returning by an easy curve to its seat near the upper edge; a flower rises upon the outer surface of the dish from the lower end of the handle. The dish is provided with two similar handles C C one on

each opposite side. Between the handles near the upper edge of the dish is a scroll ornament D. The upper margin of the dish is provided with a series of vertical flutes B, 25 terminating in the edge and gradually passing out into the smooth body of the dish at a point midway between the top and bottom. Similar fluted corrugations are formed upon the base E. The cover A is provided at its 30 extreme top with a finial ornamentation a, which may be used as a handle.

What I claim is:

The design for dishes substantially as shown and described. 35

In testimony whereof I affix my signature in presence of two witnesses.

THEODORE HAVILAND.
